UNITED STATES PATENT OFFICE.

ROBERT W. GORMLY, OF TROY, NEW YORK.

CIRCULAR-KNITTING MACHINE.

1,117,032.

Specification of Letters Patent. Patented Nov. 10, 1914.

Application filed April 28, 1914. Serial No. 834,960.

To all whom it may concern:

Be it known that I, ROBERT W. GORMLY, citizen of the United States, residing at Troy, in the county of Rensselaer and State 5 of New York, have invented certain new and useful Improvements in Circular-Knitting Machines; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification. 15

This invention relates to improvements in circular knitting machines employing ordinary spring needles.

The object of my invention is to provide 20 spring needle knitting machines for producing an elastic fabric having much of the appearance and many of the characteristics of ribbed fabric.

According to this invention the spring 25 needles are arranged in staggered relation and the bur wheels are constructed to co-operate with the needles so that rows of loops, which alternate with each other, according to the staggered arrangement of 30 the needles, are produced, making the surface of the cloth corrugated, so to speak, one row being higher and the other being lower, in relation to the mean surface of the cloth.

The invention also comprehends improvements 35 in the details of construction and arrangement of parts which will be herein-after described and particularly pointed out in the claims.

In the accompanying drawings: Figure 1 40 is a plan view of a portion of a circular knitting machine illustrating my invention. Fig. 2 is an enlarged face view of the fabric. Fig. 3 is a detail side elevation of a set of needles and the base. Fig. 3^a is a 45 plan view of the same. Fig. 4 is a diagrammatic plan view of the operating parts. Fig. 5 is a diagrammatic side elevation of the parts shown in Fig. 4.

1 indicates the cylinder of a circular knitting 50 machine and arranged around the upper surface and near the edge are the usual needle leads 2. Extending upwardly from each lead are two spring needles 3 and 4, one being set back farther than the other.

55 Each spring needle is of the usual and well known type, the beard 5 being clearly shown

in Fig. 3. When the leads are assembled in the cylinder, the needles 3 and 4 form the staggered row of needles 6 and 7.

Mounted on a suitable support 8 and disposed at an angle to the needles, is a bur wheel 9, the blades of which are alternately short and long coöperate with the needles 3 and 4. In advance of and on the inside of the bur wheels and the needles is the usual push down wheel 10. Spaced from the bur wheel 9 and disposed so as to act on the outer surfaces of the needles is a presser wheel 12, formed with a series of shallow depressions 13 and an alternate series of deeper depressions 14, which engage respectively the beards of the staggered row of needles 4 and 3. Mounted on a support 15 inside the needles and coöoperating with the presser wheel 12, is an inclined landing wheel 16 which operates to land the loops over the beards in the usual manner. Spaced from the landing wheel 16 and operating inside the needles is an inclined cast off wheel 17, which casts the loops from the inwardly staggered needles in the formation of the fabric. Because of the staggered arrangement of the needles, I find it preferable to dispose an inclined cast off wheel 18 outside the row of needles, which casts the loops from the outwardly staggered needles, which together with cast off wheel 17 perform that function uniformly and evenly for the entire row of staggered needles.

In operation, the yarn 20 passes over a 90 guide 21 to the ends of the blades, placing the yarn inside the beards of the needles, as clearly indicated in Fig. 5. Because of the staggered arrangement of the needles the yarn lies in a zigzag path in the upper ends 95 of the beards as shown in Fig. 4. During this time the cylinder carrying the needles is revolved and the blades of the landing wheel 16 elevate the previously formed loops over the closed beards 5 of the needles, the beards 100 being closed by the presser wheel 12.

As previously stated, the presser wheel is provided with two sets of notches, the walls of which act on the beards of both the in and out staggered needles, to permit of the 105 landing of the respective loops as indicated in Fig. 5. The loops having been landed over the beards, the cast off wheels 17 and 18 act to cast off the loops in the well known manner.

Obviously, since the blades of the stitch wheel 9 are staggered, and the needles 6 and

7 upon the cylinder 1, with which the stitch wheel 9 coöperates, are also staggered, the result obtained in the fabric is rows of loops 30 and 31, which alternate in and out 5 in harmony with the staggered row of needles 6 and 7 and the staggered blades of the stitch wheel 9, which gives a ribbed effect on the face of the fabric and also produces extreme elasticity, as shown in Fig. 2 10 of the drawing. In fact the finished product is to all intents and purposes substantially a ribbed fabric produced with a single set of spring needles, which result is obtained by staggering the needles and blades 15 of the stitch wheel.

As knitting machines employing spring needles and the operation of the same are so well known, it is not thought necessary to describe specifically all the various steps of 20 knitting, for the reason that my invention is directed primarily to the disposition of the spring needles and the various forms of wheels coöperating therewith.

It is well known that by setting the stitch 25 wheel 9 in or out the loops may be made longer or shorter as desired. Then again it is not absolutely necessary that the needles be arranged alternately as shown and described, for they may be placed in alternate 30 groups, according to the design desired.

Having thus described my invention, what I claim is:—

1. A circular knitting machine, comprising a rotating ring, a plurality of stationary 35 spring bearded needles arranged in zigzag form in said rotating ring, means for feeding yarn to said needles, and wheels coöperating with the needles to knit fabric with rows of zigzag loops.

40 2. A circular knitting machine comprising a rotating ring, a plurality of spring bearded needles, which are staggered in their relative position with respect to each other, and which are fixed to the rotating ring, means 45 for feeding yarn to the needles and means coöperating with the needles to knit fabric formed with zigzagged loops.

3. A circular knitting machine comprising a rotating ring, a plurality of spring 50 bearded needles, certain of said needles being arranged out of alinement with the ad-

jacent needles, all said needles being fixed to the rotating ring, means for feeding yarn to the needles, and means coöperating with the needles to knit fabric formed with alternate rows of loops. 55

4. A circular knitting machine comprising a plurality of spring bearded needles arranged in zigzag relation, a bur wheel for feeding yarn to the needles, said bur wheel 60 having blades of different lengths to coöperate with the zigzagged needles, a presser wheel to engage the beards of the said needles in their zigzag relation with each other, a landing wheel to coöperate with the presser 65 wheel to elevate the loops over the beards of the needles, and a cast off wheel to cast the loops from the needles.

5. A circular knitting machine comprising a plurality of spring bearded needles, 70 certain needles being staggered or displaced out of alinement with certain other of the needles, a bur wheel having long and short blades to coöperate with the needles and feed yarn to the latter, a presser wheel to close 75 the beards of the needles, a landing wheel to land the loops of yarn over the beards closed by the presser wheel, and a cast off wheel to elevate the loops from the needles.

6. A circular knitting machine comprising a plurality of spring bearded needles arranged in zigzag relation, a bur wheel for feeding yarn to the needles, said bur wheel having blades of different lengths to coöperate with the needles, a presser wheel to 80 engage the beards of the needles, a landing wheel to coöperate with the presser wheel to elevate the loops over the beards of the needles, a cast off wheel on the inside of the 85 row of needles to cast off the loops from the 90 instaggered needles, and a cast off wheel on the outside of the row of needles to cast off the loops from the outstaggered needles, or the loops which have not been cast off by the first mentioned cast off wheel. 95

In testimony whereof I have signed my name to this specification in the presence of two subscribing witnesses.

ROBERT W. GORMLY.
